CLAIM

The ornamental design for a beverage capsule, as shown and described.

DESCRIPTION

FIG. 1 is a perspective view of a beverage capsule, showing my new design;

FIG. 2 is a front view thereof;

FIG. 3 is a right thereof;

FIG. 4 is a left view thereof;

FIG. 5 is a rear view thereof;

FIG. 6 is a top thereof; and,

FIG. 7 is a bottom view thereof.

The broken lines shown in the drawings depict portions of the beverage capsule that form no part of the claimed design.
